DISPLAY STAND

Roger F. Rex, Hales Corners, Wis., assignor to Display Corporation, Milwaukee, Wis., a corporation of Wisconsin

Filed June 21, 1963, Ser. No. 75,471

Term of patent 7 years

(Cl. D80—9)

FIG. 1.

FIG. 3.

FIG. 2.

FIG. 4.

FIG. 5.

FIG. 7.

FIG. 6.

FIG. 1 is a top plan view of a display stand embodying my new design;

FIG. 2 is a side elevation thereof taken from the left side in FIG. 1;

FIG. 3 is a side elevation thereof taken from the right side in FIG. 1;

FIG. 4 is a bottom plan view thereof;

FIG. 5 is a section view taken generally along lines 5-5 of FIG. 3;

FIG. 6 is a front perspective thereof; and

FIG. 7 is a rear perspective thereof.

The dominant features of my design reside in the portions shown in full lines. It is to be understood that

the spaced vertical lines on the bottom front panels shown in FIGS. 2 and 6 represent grooves.

I claim:

The ornamental design for a display stand, substantially as shown and described.
